United States Patent Office

Des. 214,711
Patented July 15, 1969

214,711

GUN CASE

Clarence J. Sweet, 19480 Mackay 48234, and Everett W. Sweet, 19171 Keating 48203, both of Detroit, Mich.

Filed Mar. 6, 1968, Ser. No. 10,864

Term of patent 14 years

Int. Cl. D22—04; D3—99

U.S. Cl. D87—1

FIG. 1

FIG. 2

FIG. 3

FIG. 4

FIG. 5

FIGURE 2 is a perspective view of the gun case in its open position; and

The broken line illustration in FIGURE 2 indicates the position which would be occupied by a gun received within the gun case.

We claim:

The ornamental design for a gun case, as shown and described.
